UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

DESIGN FOR A CONTROL HANDLE FOR REGULATING APPARATUS.

Application filed June 5, 1924. Serial No. 9,808. Term of patent 7 years.

To all whom it may concern:

Be it known that I, EDWARD B. NOWOSIELSKI, a citizen of the United States, residing at Bloomfield, in the county of Essex, State of New Jersey, have invented a new, original, and ornamental Design for a Control Handle for Regulating Apparatus, of which the following is a description, reference being had to the accompanying drawing, forming a part hereof.

Figure 1 is a front elevation and Figure 2 a perspective view of the control handle, showing my new design.

I claim:

The ornamental design for a control handle for regulating apparatus as shown.

In testimony whereof, I affix my signature.

EDWARD B. NOWOSIELSKI.
